United States Patent Office.

J. NEWTON THATCHER, OF MARTINSBURG WEST VIRGINIA.

Letters Patent No. 90,473, dated May 25, 1869.

IMPROVED CARRIAGE-JACK.

The Schedule referred to in these Letters Patent and making part of the same.

To all whom it may concern:

Be it known that I, J. NEWTON THATCHER, of Martinsburg, in the county of Berkeley, and State of West Virginia, have invented a new and improved Wagon Jack; and I do hereby declare that the following is a full, clear, and exact description thereof, which will enable others skilled in the art to make and use the same, reference being had to the accompanying drawing, forming part of this specification.

This invention relates to improvements in jacks for raising carriage-wheels off the ground, to facilitate the removal of them for lubricating and other purposes.

It consists in the arrangement, upon a suitable stand, of an elevating-lever, having an adjustable fulcrum on the said stand, for vehicles of different heights, and a holding-bar, for holding the lever when the vehicle has been raised up, all as hereinafter fully specified.

The drawing represents a side elevation of my improved jack, supporting a wheel in the elevated position.

A represents a stand, having a foot, B, considerably elongated in the direction C.

D represents an elevating-lever, having a fulcrum in the top of the stand, which may be adjusted vertically or longitudinally.

Also, a notch, or groove, E, in the end of the short

arm, wherein the axle of the vehicle is designed to rest.

The long arm of the lever is provided with a metallic loop, F, at one side, wherein the free end of a holding-bar, G, slides, and on to which it catches by means of a notched bar, H, secured thereto. The other end of the said holding-bar is jointed to the foot B.

In swinging down the long arm of the lever D, to raise an axle, the loop F will slide along the holding-bar, and the notched bar will catch upon the loop and hold the lever D down.

The elongation of the foot B, at C, beyond the length of the short arm, prevents the stand from falling over in that direction, and the wheel, opposite to that raised, prevents falling laterally.

Having thus described my invention, I claim as new, and desire to secure by Letters Patent—

The combination with the stand A, having an elongated foot, of the lever D, notched holding-bar G, and loop F, all substantially as specified.

J. N. THATCHER.
